UNITED STATES PATENT OFFICE.

WILLIAM J. GROTHUIJS, OF ELKHART, INDIANA, ASSIGNOR TO SANITARY STEEL COUCH COMPANY, OF CHICAGO, ILLINOIS, A CORPORATION OF ILLINOIS.

BED OR COUCH.

987,064.

Specification of Letters Patent. Patented Mar. 14, 1911.

Application filed April 2, 1909. Serial No. 487,414.

To all whom it may concern:

Be it known that I, WILLIAM J. GROTHUIJS, a citizen of the United States of America, and resident of Elkhart, Elkhart 5 county, Indiana, have invented a certain new and useful Improvement in Beds or Couches, of which the following is a specification.

Beds and couches have been heretofore 10 made in many ways. Some have been constructed to fold, and others have been made in sections which are movably connected to reduce or extend the area of the top. These have been used to a large extent, but they 15 have not met all requirements. Both folding and sectional beds or couches are liable not to be as substantial and free from complications as might be desired. Folding couches, and extensible beds or couches composed of relatively sliding sections, are, 20 moreover, liable to get out of order and refuse to work properly when it is desired to open or close them. Then again the folding or extensible couch, such as the bed or couch 25 composed of sections—a main section and a sliding section—are not capable of separation to form two separate couches or beds. Also, the bed or couch made in sections, one sliding upon the other, does not insure a 30 perfectly flat top when the two sections are drawn apart, as the top of the main section is generally much higher than the sliding section. This last objection has, in certain cases, necessitated thicker padding at one 35 side than at the other, in order to make the bed level. Couches have been made to slide one under the other, each being a complete and rigid or non-adjustable couch. Here, also is the objection that the top is not 40 level when the couches are placed side by side. Thicker padding was necessary here as with the sectional or extensible couch. The lower fabric has been raised to the level of the higher of the two couches, in some 45 cases. This, also, was not satisfactory, as the fabric could not overlap, and hence the degree of extension could not be varied.

My invention contemplates, therefore, a 50 pair of separate couches, or twin beds, as they might be called, of such character that one will go over or under the other, when it is desired to put one out of the way, and of such character that they can be used either separately or together, as may be desired,

without the necessity of any sliding or other 55 connections between them, such as are ordinarily and necessarily used between folding or sliding sections of the same couch or bed, and in which provision is made for equalizing the height of the two beds or couches, 60 by lowering one relative to the other, whereby a perfectly level area is presented by the combined tops of the two couches, or by the combined tops of two or more sections of 65 the same couch, depending upon the construction, the two separate couches being, however, the preferred arrangement for leveling two or more fabrics or other supporting mediums.

It further contemplates the augmenting 70 of the strength and stability of one supporting medium of a bed or couch, by lowering on to the same, at will, another medium, such as a metallic fabric, whereby the character of the support upon which the person 75 rests may be changed at will.

It also contemplates two couch fabrics, one adapted to overlap the other, and means for varying the extent to which one overlaps the other, whereby the width of the bed 80 may be varied.

In the accompanying drawings—Figure 1 is an end elevation of two couches or twin beds, one rolled partially over the other, whereby the two may be used to form a 85 double bed. Fig. 2 is a plan of the couches or beds shown in Fig. 1, the central portion thereof being shown broken away for convenience of illustration. Fig. 3 is an enlarged cross section of one couch or bed, showing a portion of the other. Fig. 4 is an enlarged detail plan view of the overlapping portion 90 of the fabrics at one end of the two couches. Fig. 5 is a detail section on line 5—5 in Fig. 4. Fig. 6 is a perspective of one of the sliding legs of one of the couches. Fig. 7 is a 95 perspective of one of the attaching hooks for certain of the helical springs of the fabric of one of the couches.

As thus illustrated, the two couches or 100 twin beds A and B are substantially alike, except that the latter is slightly smaller—that is, slightly shorter. The couch or bed A has the usual top of metallic fabric a, and the couch or bed B has a similar top 105 of fabric b. Legs a' are provided for the couch or bed A, and legs b' are provided for the couch or bed B. Casters a² and b²

are provided for the lower ends of said legs. The frame construction of each couch or bed is unimportant, and may be of any suitable character, such as those used for various well known forms of steel couches. If the ordinary side bars a^3 and b^3 are used, then the two couches are separated by tilting them over on their sides and drawing the legs a' through the space between the bars 10 b^3 and the fabric b . The two couches are then brought one over the other by the reverse process. These side bars are, however, not necessary, as other provisions may be used. The couch or bed B is adapted to 15 roll over the couch A, thus putting the latter out of the way. When separated the two couches or beds make separate couches or beds which can be used in different parts of the room, or in different rooms. When 20 brought together the two couches or beds form twin beds for sleeping purposes.

As a matter of special improvement, the couch or bed B has sliding feet or legs C operated by toggles D. It will be seen that 25 each toggle (there are four in all) has one end pivoted to the legs b' and the other end pivoted to the foot or sliding leg C. The joints or middle parts of these toggles are connected by links E with levers F mounted 30 on a suitably supported rod or shaft G. One or both of said levers F may be provided with a handle f. As shown, the toggles D are in position to hold the couch B in an elevated position—that is, with its top some- 35 what higher than the top of the couch A. This is because the toggles are moved a little past the center and are bearing against the flanges of the angle iron legs. When the lever F is swung over, the toggles are bent 40 in the other direction to an extent sufficient to permit the fabric b to rest on the fabric a . The fabric shown is made up of longitudinal slats and cross connecting links. Helical springs connect the slats to the ends 45 of the two couch frames. The helicals H for the couch B are connected to the couch frame by hooks h which rest on the ends of the frame of the couch A when the upper fabric is lowered on to the other. When this 50 is done, the slats 1 of the couch B fall between the slats 2 of the couch A.

In use the two fabrics can be lapped either slightly or to a considerable extent, depending upon what width of bed is desired. In 55 any case, however, the interlocking of the two fabrics will hold the two couches against relative movement. When one couch or bed is moved entirely over the other, then the two fabrics can be left separated, or they 60 can be brought together. Thus one supporting medium is lowered to augment the strength and stability of a supporting medium below. When partially separated, the two couches form a double bed; when 65 fully separated, they constitute twin beds, or

may be used as two separate couches. The lapping of the fabrics a and b , and the lowering of one on to the other, brings them practically into the same plane, and gives 70 a broad level surface. In this way different thicknesses of padding is not necessary.

The toggle mechanism determines the position of the top of the couch B, as the same has only two positions, either clear up 75 or clear down. There can be no intermediate positions; and the weight of one couch is employed for bringing its fabric down to the level of the other fabric. This is a decided advantage, as there is no weight upon the toggles or other adjusting devices 80 when the fabrics are brought into the same level. The leveling is done by taking the weight off from the raising and lowering mechanism.

If a single bed is desired, one couch can 85 be moved over the other, and the upper couch raised to its upper position. If a couch is desired, then the upper fabric can be lowered onto the other fabric, so that the two fabrics will combine to give greater 90 stability for couch purposes. The upper fabric can then be again raised for sleeping purposes.

What I claim as my invention is:

1. Two separate beds or couches, each 95 provided with means whereby it is fully supported on the floor independently of the other, one over the other, the upper couch having extensible legs for raising and lowering the top thereof relative to the other, each leg provided with a toggle inclosed therein, and means for operating said toggles simultaneously.

2. Two separate beds or couches, each 105 provided with means whereby it is fully supported on the floor independently of the other, one under the other, one couch having extensible legs for raising and lowering the top thereof, relative to the other, each leg provided with a toggle inclosed therein, and 110 means for operating said toggles simultaneously.

3. Two separate beds or couches, each 115 provided with legs whereby it is fully supported on the floor independently of the other, one over the other, and devices for shortening the legs of the upper couch.

4. Two separate beds or couches, each 120 provided with means whereby it is fully supported on the floor independently of the other in all positions of both couches, and means adapting one to be moved over the other, comprising devices on the upper bed or couch for lowering its top into the plane of the top of the other bed or couch.

5. Two separate beds or couches, each 125 provided with means whereby it is fully supported on the floor independently of the other in all positions of both couches, one being smaller to move under the other, and

means on the upper bed or couch for lowering its top into the plane of the top of the other bed or couch.

6. Two separate beds or couches, each 5 provided with means whereby it is fully supported on the floor independently of the other in all positions of both couches, one over the other, each bed or couch being separable from and adapted for 10 use independently of the other, one couch being extensible, legs for raising and lowering the top thereof relative to the other, the top of one couch being provided with means for interlocking with the top of the other, 15 when the two are to be used together in extended form, the interlocking means consisting of a fabric on one couch that meshes with a fabric on the other couch.
7. Two independent bed or couch fabrics, 20 and means comprising a movable frame supporting one fabric for lapping and interlocking the side portions of said fabrics, to provide a bed of extended area, said means operable to separate them afterward.
8. Two bed or couch fabrics, one disposed 25 in a plane above the other, means for lowering the upper fabric into the plane of the other, and means for supporting the fabrics in either position.

9. In beds or couches, two supporting 30 mediums, means for moving the upper medium vertically and downward upon the other to in effect combine the supporting strength of the two in one, and means for supporting the mediums in either position.
10. In a bed or couch, two supporting 35 mediums, one disposed above and resting upon the other, and adjusting means for raising the upper medium vertically and 40 bodily, as set forth.

11. In an article of furniture of the type 45 set forth, the combination of two independent couches, each couch provided with means for supporting it independently of the other in all positions of both couches,

each couch provided with an upper supporting surface of fabric, one of these couches having its frame as well as its supporting fabric made shorter than the other, and said other couch being provided with 50 means for raising and lowering the fabric thereof whereby the two couches may be detached and used separately or may be telescoped one into the other for the purpose set forth. 55

12. An article of furniture of the type set forth, consisting of two couches, each couch having an upper supporting surface of resilient material, the frame as well as the resilient supporting surface of one of 60 the couches being shorter than that of the other, and said other couch being provided with means for raising its supporting surface above the supporting surface of the other couch, and for lowering it into the 65 same plane therewith, the said raising and lowering means being located entirely upon said other couch, whereby the couches may be telescoped to varying extents and the two fabrics brought together in the same 70 plane in each of the adjustments, for the purpose set forth.

13. A couch having means for converting the same into a bed, comprising upper and lower members, each member having means 75 for supporting it independently of the other member in all positions of both members, the supporting means of the upper member being adjustable, and operating means connected to said adjustable supporting means 80 whereby the upper member is adapted to be moved over and upon or to a level with and beside the lower member.

Signed by me at Chicago, Illinois, this 4th day of February, 1909.
